METHOD AND APPARATUS FOR COATING CORES

Filed Feb. 26, 1923

UNITED STATES PATENT OFFICE.

HENRY FLEETWOOD ALBRIGHT, OF OAK PARK, ILLINOIS, ASSIGNOR TO WESTERN ELECTRIC COMPANY, INCORPORATED, OF NEW YORK, N. Y., A CORPORATION OF NEW YORK.

METHOD AND APPARATUS FOR COATING CORES.

Application filed February 26, 1923. Serial No. 621,219.

This invention relates to a method and apparatus for coating cores.

The object of the invention is to produce a core having a coating of pulp thereon which is attached to the core solely by an intermingling of the fibers thereof and without the use of any adhesive substance.

Another object of the invention is to coat a plurality of cores in strand form simultaneously.

Briefly, the method consists in depositing wet pulpois material on a screen or other suitable foraminous member, transferring the material from said member to a carrier, preferably a felt, removing the material from the felt in ribbon form and slitting the said ribbon into a plurality of narrower ribbons, pressing the said ribbons on the cores to be coated and then forming said material on the cores to constitute homogeneous coatings therefor.

The present method may be employed to advantage for insulating electrical conductors, but it is to be understood that it is not limited to this purpose but only in so far as is defined by the appended claims. Where the method is used for insulating electrical conductors manila, wood rag, cotton, esparto, jute, hemp, and asbestos pulps may be employed as the coating material, but other materials than those specified may be used without departing from the spirit and scope of the present invention which contemplates in its broadest aspect the coating of any core with pulp.

The drawings illustrate an apparatus by which the method may be practiced, the apparatus being especially designed for coating cores in strand form, but it is to be understood that other apparatus may be devised for coating cores in other forms without departing from the spirit and scope of the invention.

The word "pulp" as used in the specification and claims is to be understood as defining and including any cohering fibrous mass whether suspended in a liquid, moist, or substantially dry.

In the accompanying drawings,

Fig. 1 is a side elevation of a preferred apparatus by which the method may be practiced;

Fig. 2 is an enlarged, fragmentary, top

plan view of part of the apparatus shown in Fig. 1;

Figs. 3, 4, 5, and 6 are enlarged, sectional views showing the form of the pulp coatings as they pass through the first set of squeeze rolls and are delivered from the carrier, the second set of squeeze rolls, the slitting mechanism and, the third set of squeeze rolls, respectively, and

Figs. 7 and 8 are enlarged sectional views showing the form of the pulp coatings during the forming operation and after the completion of the forming operation respectively.

The steps of the method will be readily understood from a detailed description of the apparatus by which the method may be practiced.

Referring to the drawings in detail in which like reference numerals designate similar parts throughout the several views, the apparatus comprises a drum 10 which is partially submerged in a liquid containing pulp within a trough 11. The drum 10 comprises a pair of sheet metal sides and a peripheral portion 12 secured thereto. The portion 12 is provided with a plurality of relatively large perforations 13 which are covered with a narrow strip of fine wire mesh 14, as shown in Fig. 2. The drum has a centrally disposed tubular axle 15 which is rotatably mounted in suitable bearings 16 carried by a framework 17 which supports all of the elements of the apparatus.

Pulpois material is strained onto the wire mesh 14 as the drum 10 is rotated in the tank by maintaining the level of the mixture within the drum 10 at a lower level than that of the pulp liquid in the tank 11, as indicated by dotted lines A and B respectively. This difference in levels is maintained by a syphon pipe 18 which has its inlet opening submerged in the liquid within the drum and its discharge through the tubular axle 15. A continuous circulation of pulp liquid is maintained in the tank 11 by feeding the pulp liquid from a supply tank (not shown) into the tank 11 by means of a pipe 19 and out of said tank through a pipe 20 into a receiving tank (not shown) from which it is pumped back into the supply tank in any suitable manner. As the drum 10 rotates in the tank 11, due to the

difference in levels of the liquid in the drum and tank, the liquid in the tank will pass through the wire mesh 14 and perforations 13 straining the pulp onto the outer surface of the wire mesh.

Disposed in contact with the wire mesh 14 is a belt 21 preferably made of felt and revolvably mounted upon rollers 22 and 23 rotatably mounted within suitable bearings 5 carried by spaced brackets 24 which are supported by the framework 17. The drum 10 and felt belt 21 are driven in the directions indicated by the arrows by means of belts connected with a suitable driving mechanism 15 (not shown). The roll 22 is so disposed relative to the drum 10 that the felt belt 21 is squeezed between it and the fine wire mesh 14, which serves to remove the "free liquid" from the pulp material and also to transfer 20 the material from the wire mesh to the felt in a manner well understood by those skilled in the art. The pulpos material on the felt 21 is carried thereby between the roll 23 and a felt covered roll 25, these rolls being forced 25 together by any suitable pressure means which may be adjustable to present the proper pressure on the pulpos material. The rolls 23 and 25 serve to remove additional moisture from the pulpos material 30 and felt the fibers thereof together sufficiently to permit the material to be taken from the felt, in the form shown in Fig. 3, and fed between a pair of squeeze rolls 26 and 27 rotatably mounted within suitable bearings 35 carried by the parallel frameworks 24. The roll 27 is driven by a belt connected with any suitable source of power (not shown). The rolls 26 and 27 serve to draw 40 the pulpos material from the felt belt 21 and feed it to a cutting disk 28 operating upon the periphery of a drum 29. The pulpos material is delivered from the squeeze rolls 26 and 27 in the form of a moist and cohering sheet as shown in Fig. 4, the 45 ribbon being of such consistency that it may be slit by the cutting disk 28.

The cores to be coated, which are illustrated as being two in number, are fed from suitable supply spools 30 over idler rolls 31, 50 between the squeeze rolls 26 and 27, and beneath the pulpos material as the said material passes between these rolls. The cores and pulpos ribbon are fed together to the cutting disk 28, the cores lying upon the 55 drum 29 with the edges of the pulpos sheet projecting beyond each core as shown in Fig. 5.

The squeeze rolls 26 and 27 serve to attach the wide pulpos ribbon to the two cores to 60 some extent, so that when this sheet is slit by the cutter 28 into two ribbons each core and its associated ribbon tends to remain in close contact, the cores being disposed substantially in the center of the ribbons, as 65 shown in Fig. 5. From the cutting disk 28

the two ribbons and their associated cores are passed between pairs of squeeze rolls 40 and 41 disposed above each other in the manner shown. These squeeze rolls serve to remove additional moisture from the pulpos 70 ribbons and to force them into more intimate engagement with their associated cores as shown in Fig. 6.

From the pairs of squeeze rolls 40 and 41 each of the cores with its associated ribbon is drawn through forming mechanisms 33 and 34 which are associated with the pairs of squeeze rolls 40 and 41 respectively. The formers 33 and 34 wrap the projecting edges of the ribbons around the cores and 75 around each other, the appearance of the coatings after they are first acted upon by the formers and after the forming action is completed being clearly shown in Figs. 7 and 8 respectively. Each of the formers 80 causes a thorough intermingling of the pulp fibers and shapes the coatings so that it embraces the core and conforms to the shape thereof and molds the coating into a mass so homogeneous that upon cutting the core and coating, the latter will not fray or ravel and 85 will not become easily detached from the core.

Each of the formers 33 and 34 comprises 90 essentially two plates which are rotated around the core and serve to wrap the pulp ribbon around the core in much the same manner as though the core and pulp ribbon were rolled on a table top with the palm of the hand. The formers 33 and 34 shown 95 in the drawings are identical with that fully described in the co-pending application of Walker and March, Serial No. 547,923, filed March 29, 1922, and for a detailed description 100 of this mechanism reference is made to the application above referred to.

Each of the coated cores is drawn from 105 its associated former and subjected to a mechanism for thoroughly drying the coating. The means shown for performing this 110 operation comprises pairs of wide hollow drums 35 and 36 internally heated and having a plurality of grooves formed thereon (not shown) which receive the coated cores, guides (not shown) being provided for directing the cores over first one drum of each pair and then over the other drum until it has traversed all of the grooves on both 115 drums, after which the cores are stored on take up spools 37 and 38 respectively. The 120 drying apparatus shown is identical with that fully illustrated and shown in the Walker-March co-pending application above referred to and for a full disclosure of this 125 apparatus, reference is made to the said application.

The apparatus illustrated and above described is adapted to simultaneously coat two cores in strand form, but it is to be understood that the machine may be modified and 130

parts duplicated to simultaneously coat a larger number of cores without departing from the spirit and scope of the present invention.

5. Although it has been stated that the primary object of the invention is to apply a coating of pulp to a core without the use of any adhesive substance, the machine herein disclosed may be used with a pulp mixture containing a sizing substance, or the pulp may be deposited on a core which has been previously treated with an adhesive agent, without departing from the spirit and scope of the present invention.

15. What is claimed is:

1. The method of coating a core with pulp which consists in depositing pulpous material on a member, removing said material from the member, applying a core to said material, separating a portion of said material from the whole, and then forming said portion of said material on the core to constitute a coating therefor.

2. The method of coating a core with pulp, which consists in depositing wet pulpous material on a member, removing said material from the member and removing some of the moisture therefrom, separating a portion of said material from the whole, causing said portion of said material to be brought into more intimate contact with a previously presented core, forming said material on the core to constitute a coating therefor, and then removing substantially all of the moisture from said coating.

3. The method of coating a core with pulp which consists in depositing pulpous material on a member, transferring said material from the member to a carrier, removing said material from the carrier and separating a portion of said material from the whole and pressing said portion thereof on the previously presented core, and then forming said material on the core to constitute a coating therefor.

4. The method of coating cores with pulp which consists in depositing pulpous material on a member, removing said material from the member and separating the material into portions sufficient for each core, pressing the separated portions of the material on the previously presented cores and then forming said material on the cores to constitute a coating therefor.

5. The method of simultaneously coating a plurality of cores with pulp which consists in depositing pulpous material on a member, transferring said material from said member to a carrier, removing said material from said carrier and separating the material into portions sufficient for each core, pressing the separated portions of material on the previously presented cores and then forming said material on the cores to constitute a coating therefor.

6. The method of simultaneously coating a plurality of cores with pulp which consists in depositing wet pulpous material on a member, removing said material from the member and removing some of the moisture therefrom, separating the material into portions sufficient for each core, pressing the separated portions of material on the previously presented cores, and then forming said material on the cores to constitute a coating therefor.

7. The method of simultaneously coating a plurality of cores with pulp which consists in depositing pulpous material on a member, removing said material from the member in sheet form and separating the sheet into ribbons, pressing the ribbons on the previously presented cores, and then forming said ribbons on the cores to constitute a coating therefor.

8. The method of simultaneously coating a plurality of cores with pulp which consists in depositing wet pulpous material on a member, removing said material from the member in sheet form and removing some of the moisture therefrom, separating the sheet into ribbons, pressing the ribbons on the previously presented cores, and then forming said ribbons on the cores to constitute a coating therefor.

9. The method of simultaneously coating a plurality of cores with pulp which consists in depositing wet pulpous material on a member, transferring said material from said member to a carrier and removing some of the moisture therefrom, removing said material from the carrier in sheet form, separating the sheet into ribbons, pressing the ribbons on the previously presented cores, and then forming said ribbons on the cores to constitute a coating therefor.

10. The method of simultaneously coating a plurality of cores which consists in depositing wet pulpous material on a member, transferring said material from said member to a felt and removing some of the moisture therefrom, removing said material from the felt in sheet form, cutting the sheet into ribbons, pressing the ribbons on the previously presented cores, and then forming said ribbons on the cores to constitute a coating therefor.

11. The method of coating cores in strand form with pulp which consists in depositing pulpous material on a member, removing said material from the member in sheet form, separating the sheet into ribbons, pressing the ribbons on the previously presented cores longitudinally of the cores and then wrapping said ribbons around the cores.

12. The method of coating cores in strand form with pulp which consists in depositing wet pulpous material on a member, removing said material from said member in sheet form and removing some of the moisture

- therefrom, separating the sheet into ribbons, pressing the ribbons on the previously presented cores longitudinally of the cores and then wrapping said ribbons around the cores.
13. The method of coating moving cores in strand form with pulp which consists in depositing wet pulpy material on a member, removing said material from said member in sheet form and removing some of the moisture therefrom, separating the sheet into ribbons, pressing the ribbons on the previously presented moving cores longitudinally of the cores and then wrapping said ribbons around the cores.
14. In a machine for coating cores with pulp, a receptacle for holding a supply of liquid containing pulp, a member, means for causing relative movement between said member and said liquid whereby pulp is deposited on said member, means for removing said material from said member, means for separating said material into separate portions, means for pressing said portions on the previously presented cores, and means for forming said portions on the cores to constitute coatings therefor.
15. In a machine for simultaneously coating a plurality of cores in strand form with pulp, a receptacle for holding a supply of liquid containing pulp, a member, means for causing relative movement between said member and said liquid whereby pulp is deposited on said member, means for removing said pulp from said member in sheet form, means for cutting said sheet into ribbons, means for simultaneously pressing said ribbons on the previously presented cores to be coated, and means for forming the said ribbons on the cores to constitute coatings therefor.
16. In a machine for coating cores with pulp, a receptacle for holding a supply of liquid containing pulp, a member, means for causing relative movement between said member and said liquid whereby pulp is deposited on said member, means for removing said pulp from said member in sheet form and removing some of the moisture from said material, means for slitting said sheet into ribbons, means for pressing said ribbons on the previously presented cores, and means for forming said ribbons on the cores to constitute coatings therefor.
17. In a machine for coating cores with pulp, a receptacle for holding a supply of liquid containing pulp, a member, means for causing relative movement between said member and said liquid whereby pulp is deposited on said member, a carrier, means for causing engagement between the carrier and the pulp on the member whereby the pulp is transferred to the carrier, means for removing said pulp from said carrier, means for slitting said pulp into a plurality of ribbons, means for pressing said ribbons on the previously presented cores, and means for forming said ribbons on the cores to constitute coatings therefor.
18. In a machine for coating cores with pulp, a receptacle for holding a supply of liquid containing pulp, a member, means for causing relative movement between said member and said liquid whereby pulp is deposited on said member, a felt, means for causing engagement between the felt and the pulp on the member whereby the pulp is transferred to the felt, means for removing said pulp from the felt, means for slitting said pulp into a plurality of ribbons, means for pressing said ribbons on the previously presented cores, and means for forming said ribbons on the cores to constitute coatings therefor.
19. In a machine for coating cores with pulp, a receptacle for holding a supply of liquid containing pulp, a member, means for causing relative movement between said member and said liquid whereby pulp is deposited on said member, a rotatable felt disposed in engagement with said member, whereby the pulp is transferred to said felt, pressure rolls for drawing the pulp off of said felt, means for slitting said pulp into a plurality of ribbons, pressure rolls for pressing said ribbons on the previously presented cores, and means for forming said ribbons around the cores to constitute homogeneous coatings therefor.
20. In a machine for coating cores with pulp, a receptacle for holding a supply of liquid containing pulp, a member, means for causing relative movement between said member and said liquid whereby pulp is deposited on said member, a rotatable felt disposed in engagement with said member, whereby the pulp is transferred to said felt, pressure rolls for drawing the pulp off of said felt, means for slitting said pulp into a plurality of ribbons, pressure rolls for pressing said ribbons on the previously presented cores, and means for forming said ribbons around the cores to constitute homogeneous coatings therefor, and means for removing substantially all of the moisture from said coatings.
21. The method of coating a plurality of cores with paper which consists in depositing paper pulp on a member, removing said material from the member in sheet form and separating the sheet into ribbons, pressing the ribbons on the previously presented cores, and then fabricating said pulp ribbons into paper on the cores in the form of coatings thereon.
22. In a machine for coating cores with paper, a receptacle for holding a supply of liquid containing paper pulp, a member, means for causing relative movement between said member and said liquid whereby paper pulp is deposited on said member,

- means for removing said pulp from said member, means for separating said pulp into separate portions, means for pressing said portions on the previously presented cores, and means for fabricating said pulp into paper on the cores in the form of coatings thereon.
23. In a machine for coating a plurality of cores in strand form with paper pulp, a receptacle for holding a supply of liquid containing paper pulp, a member, means for causing relative movement between said member and said liquid whereby paper pulp is deposited on said member, means for removing said pulp from said member in sheet form, means for cutting said sheet into ribbons, means for pressing said ribbons on the previously presented cores to be coated; and means for fabricating said pulp ribbons into paper on the cores in the form of coatings thereon.
24. The method of coating a core with pulp, which consists in making a sheet of pulpy material, causing engagement of a core with said sheet of material, separating said sheet into portions, and forming one of said portions on the core to constitute an integral, continuous and substantially homogeneous coating therefor.
25. In witness whereof, I hereunto subscribe my name this fifteenth day of February, A. D. 1923.
